[57] ABSTRACT

The heating element is formed of refractory material resistant to oxidation, in the general shape of a parallelepiped. It has, in a direction perpendicular to two opposite surfaces, a nonhomogeneous structure such that when one of the two surfaces concerned is brought to a sufficiently high temperature to become electrically conducting, the other remains at a sufficiently low temperature to be thermally and electrically practically non-conducting. The structure is adapted to withstand movements due to differences in expansion. The element is made either of entirely or partially stabilized zirconia or of a definite compound of the pyrochlore type based on zirconia, of the formula $Zr_2T_2O_5$, T being a metal, especially a rare earth. It has holes and cut-outs formed in the mass of the element in a direction substantially perpendicular to that which unites said two opposite surfaces. The ratio hollow/solid is within a range of about 0.1 to 3.

HEATING ELEMENT

The invention relates to a heating element of the type formed of a refractory material resistant to oxidation, with melting point above 2,500°C, and generally known as "resistors".

In present heating elements of the type concerned—which bound individually a heating cavity by their shape or which are assembled to constitute heating cavities of any shape and size—it is necessary to provide bulky and sometimes heavy heat insulating means.

It is a particular object of the invention to overcome this drawback and to place at the disposal of the user a heating element of the type concerned which responds to the various desiderata of practice better than those existing hitherto.

The heating element according to the invention is characterised by the fact that it is of general shape close to that of a parallelopiped and that it has, in a direction perpendicular to two opposite surfaces, a non-homogeneous structure such that when one of the two surfaces concerned is brought to a sufficiently high temperature to become electrically conducting, the other remains at a sufficiently low temperature to be practically non-conductive of electricity, the said structure being adapted to support the movements due to differences of expansion.

The invention consists, apart from the above-said features, of certain other features which are used, preferably at the same time and which will be more explicitly considered below.

And it will in any case be well understood with the aid of the additional description which follows, as well as of the accompanying drawings given of course purely by way of illustrative but non-limiting example.

In the drawings:

FIGS. 1, 2 and 3 show respectively in perspective for the first and in elevation for the two others, three modifications of the first embodiment of the heating element according to the invention.

FIGS. 2a and 3a are views of FIGS. 2 and 3 along the lines 2a—2a and 3a—3a.

FIGS. 4, 5 and 6 show in elevation three modifications of a second embodiment of a heating element according to the invention.

FIGS. 4a, 5a and 6a are views along the lines 4a—4a, 5a—5a and 6a—6a of FIGS. 4 to 6.

FIGS. 7 to 10 show in perspective assemblies of several heating elements according to the invention.

FIG. 11 shows in elevation a fourth modification of the above-said first embodiment.

FIGS. 12 and 13, lastly, show respectively in elevation and in view and partial section along the lines XIII—XIII of FIG. 12, a fourth modification of the above-said first embodiment.

According to the invention and, more especially, according to those types of its application, as well as according to those embodiments of its various parts, to which it would appear that preference should be given, in order to construct a heating element of the type concerned, procedure is as follows or in similar manner.

The general shape of the said heating element, which is made of a refractory material resistant to oxidation of the type used for the manufacture of resistors, is parallel-epipedic or close to that of a parallelopiped. It has, consequently, the general shape of a brick of which the

length L is greater than the height H, itself greater than the thickness E.

Between two opposite surfaces denoted by F₁ and F₂ (in general those which are separated by a distance 5 equal to the height H of the element) and in a direction substantially perpendicular to these two surfaces, the structure of said element is not homogeneous so that when one of the two faces F₁ and F₂ namely face F₁, is brought to a sufficient temperature to become electrically conducting, the other remains sufficiently cool to remain practically non-conducting, by means of which 10 its face F₂ and the constituent material comprised between the faces F₁ and F₂, the heating element constitutes its own heat insulation. In addition, this construction is such that it withstands movements due to differences in expansion.

In practice, it is arranged that the difference in temperature between the two faces F₁ and F₂ is such that the resistance of the cool face is at least 100 times 20 higher than the resistance of the hot face.

The supply of electric current to the heating element is effected at the level of the two ends of the element taken in the sense of the length, for example by means 25 of platinum contacts.

In general, the constituent material of the elements according to the invention is partially or entirely "stabilised" zirconia in its form stable at high temperature that is to say its cubic form.

It is known that this stabilisation is obtained by the 30 addition of lime yttrium oxide, rare earth oxides, magnesia or the like.

The elements according to the invention can also be constituted of a definite compound of the pyrochlore type based on zirconia, of the formula Zr₂T₂O₅, T being 35 a metal, preferably a rare earth.

The above-said non-homogeneity of structure can be effected in different ways.

In a first embodiment, this absence of homogeneity, due to which the transmission of heat from face 1 to 40 face 2 is sufficiently limited for the face F₂ to remain at a temperature at which it is not conducting, is obtained by holes and cut-outs formed in the mass of the heating element in the direction substantially perpendicular to that which connects the faces F₁ and F₂ the ratio cavity/solid, when the constituent material of the element is partially or entirely stabilised zirconia, being selected around 0.1–0.2 to 3.

The arrangement and configuration of the above-said 45 holes and cut-outs are selected so that when the constituent material of the element which is situated in the vicinity of the face F₁ is brought to the temperature from which it becomes conducting, the electric current only passes in fact in the vicinity of the said face F₁.

In FIGS. 1, 2 and 3, there are shown three modifications of this first embodiment.

In the case of the modification of FIG. 1, the heating element, denoted as a whole by 1, comprises a plurality of the holes 2 as shown, as well as cut-outs 3 in the form of a slot along a broken line comprising parts parallel 60 to a certain length, at 3a, to the face F₁, as well as parts 3b and 3c of a general shape substantially perpendicular to the face F₁, the assembly being such that the said face F₁ is connected to the cold face F₂ by parts 4 of the element which, as a result of the selection of the cut-outs 3, are of relatively slight cross-section. Due to this constitution, the transmission of heat from the face F₁ to the face F₂ is very much reduced.

In addition, the positioning of the parts 3a is selected so that the thickness of the element at the level of the face F_1 , through which thickness the electric current passes, is relatively slight.

In practice, this thickness, denoted by D_1 in the Figure, as well as that of the parts 4 denoted by D_2 , is of the order of 1-3 to 5-10 mm.

It is advantageous to provide at the ends (taken in the sense of the length, of the element) holes of large size 5 of which the shape can be that which is apparent from FIG. 1 and which can serve, on one hand, for the suspension of the element, and, on the other hand, for the localisation of the leads for the introduction of the current 6, which are provided advantageously, as seen in the Figure, at the level of that of the edges of the holes 5 which occurs nearest the face F_1 . These current leads can be constituted by platinum plates bounded under pressure or moulded.

It may be advantageous to arrange the heating element 1 so that the temperature reached by the face F_1 is progressive over at least a part of its length. Thus, for example, it is desired in the case of the modification of FIG. 1 that the progression occurs in the direction increasing along the arrow F_1 .

To obtain this result, it suffices to select the size and the arrangement of the said holes and cut-outs so that there is a progressive increase in the resistance at the level of the face F_1 in the direction of the arrow F_1 . For example, as shown in FIG. 1, there may be conferred on the first cut-out 3 starting from the left a part 3d situated between the part 3b and the part 3a, and included so that the cross-section of the part rendered conducting on operating the element diminishes as shown.

To avoid deterioration and placing out of service of an element 1 as a result of the formation of a crack interrupting the electric current and which could start at the level of face F_1 , it is advantageous to divide as shown in FIG. 1 the face F_1 into several parallel lamellae 7a, by means of cut-outs 7b, perpendicular to the face F_1 .

This being the case, it is indicated that in the case of the modifications of FIGS. 2 and 3, the same principles as those described with regard to FIG. 1 have prevailed, although the holes and cut-outs adopted are of different shapes.

In fact, it is with the rectangles 8 and the cut-outs 9 of U or I shape in the case of FIG. 2, with circular holes 10 in the case of FIG. 3, that corresponding elements have been arranged so that the faces F_1 and F_2 are only connected by relatively narrow "bridges" P, thus sufficiently reducing the heat transmission from the face F_1 to the face F_2 . In addition, the said holes and cut-outs are selected so that—in the case of FIGS. 2 and 3 recourse is had especially to an elongated inclined cut-out 11 of which the arrangements and size are apparent from the said Figures—the electric current can only pass through the face F_1 .

As in the case of FIG. 1, the holes and cut-outs 8, 9, 10 are arranged between two holes 5 at the level of which are provided current lead-ins, not shown. Moreover, again as in the case of FIG. 1, the distribution of the holes and cut-outs 8, 9 and 10 is advantageously, as shown, selected so that there is obtained a temperature gradient in the direction of the arrow F_1 analogous to that described with regard to FIG. 1.

The cross-sections of the elements 1 according to the modifications of FIGS. 2 and 3 appear in FIGS. 2a and 3a.

Again as in the case of FIGS. 2 and 3, there are retained in the case of the embodiment of FIG. 11, at least certain of the principles which have prevailed in the constitution of that of FIG. 1. Here however, it was not sought to obtain a progressive temperature along the face F_1 . On the contrary, the cut-outs are practically symmetrical with respect to the median line XX. Although of generally different shape apparent from the Figure, there will be found again the holes 2, the cut-outs 3a and 3b and the holes 5 of the preceding embodiments. There will also be found here too with a particular shape apparent from FIG. 11, parts 4 connecting the faces F_1 and F_2 , F_1 and of the parts 3a as well as the thickness D_2 of the parts 4 respect the above-mentioned criteria.

Advantageously, there are provided cut-outs 20 perpendicular to the face F_1 , as shown and of length H from 0.5 to 3cm. The cut-outs 20 are provided at the level of the parts 4.

The element thus constituted, such as shown in FIG. 11, offers good thermal and electrical insulation, good power-temperature ratio, good suspending possibilities, especially at the level of the holes 5, good elasticity, good resistance to forces of expansion and a large heating surface.

It will be realised that on the operation of an element 1, the expansions are absorbed by the parts 4 connecting the faces F_1 and F_2 in the case of FIGS. 1 and 11, by the bridges P in the case of FIGS. 2 and 3.

Although in the case of the modifications of FIGS. 1 to 3 and 11, the ratio cavity/solid is in the neighbourhood of unity, this ratio is close to the lower limit of about 0.1 above-mentioned in the case of the advantageous embodiment of FIG. 12.

The element according to this embodiment comprises, as that of FIG. 11, a heating face F_1 of constant temperature in the useful part.

This element comprises two large cut-outs 20 of general direction parallel to F_1 forming a thickness D_1 of a heating surface F_1 (D_1 respects the above-mentioned criteria) and connected to the face F_2 by two cut-outs 21 of general direction perpendicular to F_1 , except a part 21a situated in the vicinity of the cut-outs 20 and oriented at about 45°. The cut-outs 21 open on the face F_2 . On this face F_2 the element is hence formed of three parts 22, 23 and 24 comprising respectively cavities 25, 26 and 27 of which the first and third serve for the housing of the current lead-ins (not shown and very accessible due to this construction), the second having the purpose of lightening the whole of the structure.

In the feet 25a, 25b.. 26a, 26b .. 27a, 27b .. (surrounding the corresponding cavities) there are provided holes 28 to 33 for the suspension of the element.

The part inclined at 45° of the cut-outs 21a forms a screen and ensures the heat insulation of the heating surface F_1 .

In addition to the cut-outs 20 and 21, there are provided:

cut-outs 34 of general direction perpendicular to the face F_1 and situated in the mass of the element between the cut-outs 20 and the cavities 25, 26 and 27, these cut-outs 34, through their arrangement and situation which are apparent from the Figure, ensuring good conduction of the current and localising possible fis-

sures caused by mechanical forces capable of being due to thermal shock and to centering of the constituent material;

cut-outs 35 provided in the vicinity of the ends of the elements, perpendicular and open on the face F_1 , these cut-outs playing the role of a heat shield and of releasing forces of expansion.

To enable the thickness of the heating part of heating path at the level of the face F_1 to be generally constant, there is provided between the cut-outs 20, a hole 36.

Lastly, in addition to longitudinal slots 7b similar to those provided in the embodiment of FIG. 1 and which "thermally insulate" the heating path, the face F_1 is cut-out along for example two cavities 37 and 38 which give it a T and a U profile shown in FIG. 13 by means of which a better behaviour in operation is achieved.

At the level of the face F_2 , there is advantageously provided a longitudinal cut-out 39 shown in FIG. 13.

The element according to this modification has not been also lightened as the preceding ones, the ratio cavity/solid being much less. On the other hand, it is of rapid and easy manufacture by reduction in the cut-outs which are selected so that the propagation of fissures is avoided. It is well understood that it is by reason of the higher weight that the points of suspension are multiplied.

It is self-evident and emerges from the figures that, in the case of the embodiments corresponding to FIGS. 11 and 12, the current is obliged to pass through the face F_1 .

To establish ideas, it is indicated that in the case where the constituent material of the element is zirconia with 4 percent of lime the temperature of the face F_2 will be 1,200°K when F_1 is at 2,200°K.

This being the case, in a second embodiment, there is conferred on the element 1 the above-said non-homogeneous structure along a direction substantially perpendicular to the faces F_1 and F_2 by making the said element comprise a part A of low porosity, less than 10 percent comprising especially the face F_1 which is intended to become conductive, this part with low porosity being combined with a part B of high porosity, greater than 20 percent comprising especially the face F_2 , the assembly being such that when the face F_1 is brought to a sufficient temperature to conduct electric current, the face F_2 remains sufficiently cool to be practically non-conducting.

The part with low porosity can be constituted by stabilised zirconia similar to that constituting elements 1 in the embodiments of FIGS. 1 to 3.

The part of high porosity in which the pores play the role of cut-outs in the modifications of the preceding embodiments, can be constituted by the same material as the part of dense porosity, or again of a more economical material such as $ZrO_2-Al_2O_3$ eutectic, alumina or another refractory without chemical interaction with the zirconia.

In practice, the part of low-porosity which comprises the face F_1 will have a density of the order of 4.5 and the porous part comprising the face F_2 will have a density of the order of 2.

To manufacture a refractory mass of given porosity necessary for the constitution of the part B comprising the face F_2 , recourse is had to conventional ceramic techniques, in particular moulding, pressing and sintering, (see for example "Ceramic Fabrication Processes" by W.D. Kingery, 1958, John Wiley).

Once part B has thus been constituted, the part A is attached to the part B, for example by projection, by having recourse to techniques using a plasma torch.

To establish ideas, it is indicated that to manufacture an element 1 which the distance between the faces F_1 and F_2 is 110 mm and of which the part comprising the face F_1 is formed of stabilized zirconia with a porosity of 6 percent and must be brought to a temperature of 22°K, recourse will be had as regards the part comprising the face F_2 and of which the temperature must not exceed 1,200°K at the level of the said face F_2 , to porous materials of zirconia or other refractory oxide mixtures of 35° porosity.

This being so, there is shown in FIGS. 4, 5 and 6 three possible modifications for the constitution of the elements 1 constructed according to this second embodiment.

The modifications shown in FIGS. 4 and 6 are symmetrical with respect to a median plane in the direction of the length of the element.

There are distinguished in FIG. 4 holes 5 similar to those of FIGS. 1 to 3, and in FIG. 6 attached parts 13 also forming holes 5.

As in the preceding embodiment, the current lead-ins not shown are placed against the corresponding surfaces of the parts A, at the level of the holes 5.

Due to the fact of the symmetry of the modifications of FIGS. 4 and 6, there is no temperature gradient at the level of face F_1 .

To obtain such a temperature gradient, the part A can be arranged as is shown in FIG. 5, by conferring on it a diminishing cross-section in the direction of the arrow f_1 which indicates the direction of increasing temperatures.

As shown, the element shown in FIG. 5 comprises a hole T for suspension.

FIGS. 4a, 5a and 6a show cross-sections of the elements of FIGS. 4 to 6.

The heating elements according to the invention are distinguished by excellent behaviour in operation of long duration.

Thus an element corresponding to the modification shown in FIG. 1 and of which the face F_1 has constituted the heating wall of the furnace, has operated perfectly for 500 hours. At the end of this experiment, examination of the said element enabled no deterioration or change in its characteristics to be discerned.

The quantitative values in the experiment were as follows:

50	temperature in the furnace chamber	2,073°K
	dimensions of the chamber	110 × 25 × 16 mm
	dimensions of the elemtn	220 × 110 × 30 mm
	thickness of the heating part (D ₁ , FIG. 1)	3.5 mm
	length of the heating part	120 mm
	width of the heating part	30 mm
	applied voltage	167 V
	current intensity	8.7 A
55	powder dissipated	1.45 kW

At the surface of this element, it was possible to observe at the end of the experiment zones with different colours, bounded by curves C₁, C₂, C₃ and C₄ in FIG. 1. These curves are the isotherms corresponding respectively to 1,400°K, 1,600°K, 1,900°K and 2,025°K.

By means of the heating elements according to the invention, it is possible to construct furnaces of any shape and size.

In FIGS. 7 to 10, there are shown several possibilities for the constitution of the furnaces.

In FIG. 7, firstly there is shown an arch-shaped furnace with horizontal axis, constructed by means of ele-

ments 1 with a trapezoidal cross-section of the type of those shown in FIG. 2. The various elements 1 rest on one another without it being necessary to resort to individual connections.

As is seen, the current lead-ins 6 are arranged as in the case of FIG. 1. There is shown the conductive wires 15 connecting the current lead-ins 6 to the electrical current source.

The elements 1 used for the construction of the furnace with rectangular cross-section as shown in FIG. 8 are of the type of that of FIG. 1. Here again there is shown the current lead-in 6 and the wires 15. The three elements 1 constituting the sealing of the furnace are held in place by a mechanical suspension, preferably by a refractory steel fixing.

As seen in FIG. 9, it is possible to construct a furnace with a trapezoidal arch by resorting to elements 1 of the type of that of FIG. 3, spacing element 16, non-conductive of electricity and formed for example of zirconia or porous alumina, being then inserted between two elements 1. The maintenance in position of the elements 1 and 16 with respect to one another can be effected by means of a mechanical suspension (they can also be simply positioned on one another as in building games).

The three furnaces which have just been described have a heating cavity with a horizontal axis.

On the other hand, FIG. 10 shows a modification with a vertical axis. In this case, there are used four elements 1 of the type of that shown in FIG. 1, spacing elements 17 being provided between the elements. The uniting of the elements 1 and 17 to one another is obtained by means of a shaping enclosure, containing and guiding the whole into good position.

To ensure the necessary pre-heating on starting of the constituent elements 1 of the above-said furnaces, recourse may be had in manner known in itself to a pre-heating element (not shown) introduced into the heating cavity to bring the faces F_1 of the elements constituting the furnace to the minimum temperature at which the constituent material of these elements becomes conductive.

As a result of which, and whatever the embodiment adopted, there are thus provided heating elements of which the characteristics and operation emerge sufficiently from the foregoing for it to be unnecessary to dwell further on this subject and which have, with respect to those pre-existing, numerous advantages, especially those:

of ensuring their own thermal insulation;

of enabling the construction of furnaces with a horizontal or a vertical axis and with a heating cavity having any desired heating gradient;

of having, due to the absence of mechanical strain, long life of several thousand hours continuously at 2,200°K on the element;

of ensuring good operation even in the presence of cracks in the heating element;

of enabling the construction of furnaces of numerous geometries and of various capacities;

and of operation in an oxidising atmosphere.

As is self-evident, and as emerges already from the foregoing, the invention is in no way limited to those of its types of application, nor to those embodiments of its various parts, which have been more especially indicated; it encompasses, on the contrary, all modifications.

We claim:

1. Heating element formed of refractory material resistant to oxidation, in the general shape of a parallelepiped, adapted to be heated by electric current supplied through electric contacts cladding said element, and having in a direction perpendicular to two of its opposite surfaces, a nonhomogeneous structure such that when one of said two surfaces is brought to a sufficiently high temperature by said electric current to become electrically conducting, the other remains at a sufficiently low temperature to be thermally and electrically practically non-conducting, said structure being adapted to withstand movements due to differences in expansion.

15 2. Heating element formed of refractory material resistant to oxidation, in the general shape of a parallelepiped, adapted to be heated by electric current supplied through electric contacts cladding said element, and having in a direction perpendicular to two of its opposite surfaces, a nonhomogeneous structure such that when one of said two surfaces is brought to a sufficiently high temperature by said electric current to become electrically conducting, the other remains at a sufficiently low temperature to be thermally and electrically practically non-conducting, said structure being adapted to withstand movements due to differences in expansion, constructed of at least partially stabilized zirconia, comprising holes and cut-outs formed in the mass of the element in a direction substantially perpendicular to that which unites said two opposite surfaces of which one is intended to be brought to a sufficient temperature to become electrically conducting, the ratio hollow/solid being selected in a range of about 0.1 to about 3.

3. Heating element according to claim 2, wherein the ratio hollow/solid is in the vicinity of unity.

4. Heating element according to claim 2, wherein the shape and the distribution of the holes and cut-outs are such that, on one hand the two opposite surfaces of which one must be brought to a sufficient temperature to be electrically conducting are connected to one another by portions of relatively slight cross-section and that, on the other hand, the electric current is obliged to pass through the surface of which the temperature is brought to a sufficient value for it to become conducting.

45 5. Heating element according to claim 4, wherein the distribution of the holes and cut-outs is selected so that the temperature reached by the surface through which the electric current passes is progressive along this surface.

55 6. Heating element according to claim 4, wherein the distribution of the holes and cut-outs is selected so that the temperature reached by the surface through which the electric current passes is uniform along this surface.

60 7. Heating element according to claim 1, wherein its ratio hollow/solid is in the vicinity of the lower limit of the range from 0.1 to 3 and comprising:

65 cut-outs of general orientation parallel to the heating surface, these cut-outs being connected to the non-heating surface by cut-outs of the general direction perpendicular to the heating surface, certain of the perpendicular cut-outs comprising a portion inclined at about 45° and dividing the element into several parts;

cut-outs of direction perpendicular to the heating surface and situated in the mass of the element between the cut-outs parallel to the heating surface, on the one hand, and the nonheating surface, on the other hand;

cut-outs perpendicular to the heating surface and opening on the latter in the neighborhood of the ends of the element;

and hollows opening on the nonheating surface.

8. Heating element formed of refractory material resistant to oxidation, in the general shape of a parallel-epiped, adapted to be heated by electric current supplied through electric contacts cladding said element, and having in a direction perpendicular to two of its opposite surfaces, a non-homogeneous structure such that when one of said two surfaces is brought to a sufficiently high temperature by said electric current to become electrically conducting, the other remains at a sufficiently low temperature to be thermally and electrically practically non-conducting, said structure being adapted to withstand movements due to differences in expansion wherein along a direction substantially perpendicular to the assembly of the two opposite surfaces of which one is intended to conduct the electric current, the said element comprises successively a first part with a slight porosity, less than 10 percent, comprising the surface intended to become electrically conducting, and a second part with a high porosity, greater than 30 percent.

9. Heating element according to claim 8, wherein the

first part is formed of stabilized zirconia of density of the neighborhood of 4.5 and that the second part is formed of one of the materials comprising zirconia, eutectic zirconia — Al_2O_3 and alumina alone, the density of this second part being in the vicinity of 2.

10. Heating element according to claim 9, wherein the first part comprises a section decreasing in the direction of the length of the heating element.

11. Heating element according to claim 1, wherein the surface through the electric current passes is divided into lamellae, parallel to one another, by cut-outs perpendicular to the said surface in the direction of the length of the element.

12. Heating element according to claim 1, wherein the heating surface comprises hollows giving it a T and U structure, along a section perpendicular to the direction of the length.

13. Heating element according to claim 1, formed of a definite compound of the pyrochlore type based on zirconia, of the formula $Zr_2T_2O_5$, where T is a metal, comprising holes and cut-outs formed in the mass of the element in a direction substantially perpendicular to that which unites said two opposite surfaces of which one is intended to be brought to a sufficient temperature to become electrically conducting, the ratio hollow/solid being selected in a range of about 0.1 to about 3.

14. Heating element according to claim 13, wherein said metal is a rare earth metal.
